UNITED STATES PATENT OFFICE.

JOSEPH A. MISLAND, OF BAYONNE, NEW JERSEY.

ELECTRICAL RESISTANCE.

1,036,304.

Specification of Letters Patent. Patented Aug. 20, 1912.

Application filed May 23, 1910. Serial No. 562,883.

To all whom it may concern:

Be it known that I, JOSEPH A. MISLAND, a citizen of the United States, residing at Bayonne, county of Hudson, and State of New Jersey, have invented certain new and useful Improvements in Electrical Resistances; and I do hereby declare the following to be a full, clear, and exact description of the invention, such as will enable others skilled in the art to which it appertains to make and use the same.

The invention relates to electrical resistances, or resistance-elements, having the characteristic that the amount of resistance offered to the flow of the electrical current may be varied without the employment of a sliding or other moving contact or the breaking of any circuit.

The object of the invention is to provide a simple and durable resistance-element of this character, suitable for use in the widest variety of places, and under the most severe operating conditions.

The nature of the invention will be made fully apparent by the following description and the accompanying drawings.

In the drawings, Figure 1 represents one of my improved resistance-elements in elevation, and drawn out beyond the extreme position which it will normally occupy in practice, for the purpose of better illustration. Fig. 2 is a central section, showing the resistance-element in its closed or short-circuited position. Fig. 3 is a plan view showing a section on the line 3-3 of Fig. 2.

The resistance-element is composed of coiled uninsulated wire, preferably made of some alloy having a high specific resistance, such as German silver, or some one of the other high resistance alloys which have more recently come into use. This coiled wire is represented in the drawings by the reference numeral 1. It is attached at one end to a conducting support 2 of copper, brass, or the like, and at the other end to a carrier 3, the support and the carrier being relatively movable with respect to one another so that they may be separated to draw the resistance wire out of contact with the conducting support, or brought together to lay the resistance wire in contact with the conducting support and thereby gradually short circuit the convolutions and correspondingly reduce the resistance of the element. In the preferred embodiment of the invention illustrated in the drawings the

conducting support is a frustum of a cone and the resistance wire is coiled into a conical spiral which, in its closed position, as shown in Fig. 2, conforms to the surface of the conical support and lies in contact with it. In this position the resistance wire is substantially short-circuited by the conducting support (or it may be completely short-circuited by bringing the carrier 3 into close conducting contact with the support 2) and the resistance is reduced to a minimum. Upon separating the support and carrier the coils of the resistance wire are successively drawn away from the conducting support and the resistance gradually increased. I find that the rate of increase of the resistance as the carrier and support are moved apart may be varied by changing the contractile force of the convolutions. If the convolutions are tight, so that the coil tends to close itself upon the support, the separation of the coil from the support, and the consequent increase of resistance, will be comparatively rapid; whereas if the convolutions are such as to lie loosely upon the support the increase of resistance will be more gradual.

It will be observed that in the drawings I have illustrated a coil in which the convolutions are so close together that when closed upon the support, as shown in Fig. 2, they lie in contact with one another. This gives the maximum length of resistance wire for a support of given size, and an additional short-circuiting effect resulting from such contact of the convolutions. In fact, with this arrangement it is not essential that the support should be of conducting material. The short-circuiting contact of the convolutions with one another may then be relied upon to bring about the gradual decrease of resistance as the coil is closed. On the other hand it is possible, as will be readily understood, to so coil the resistance wire that the individual convolutions do not lie in contact with one another when closed upon the support. In that case the support must be of conducting material to perform the short-circuiting function.

With resistance-element constructed in accordance with my invention, as above described, it is only necessary, in order to vary the resistance, to provide suitable mechanism, such for example, as a solenoid, for gradually drawing away the carrier 3 from the base, or the base from the carrier.

As will be understood by those skilled in the art, the resistance elements may be used alone or in any number, and they may be connected either in series or parallel, as the demands of the particular service required of them may suggest.

What I claim is:

1. A resistance element comprising a short-circuiting conducting support, a coil 10 of uninsulated conducting wire having one end fastened to said support, and a relatively movable carrier to which the other end of the coil is attached.
2. A resistance element comprising a short-circuiting conical conducting support, an uninsulated conducting wire coiled about 15 said support in such manner that the individual convolutions may be brought into contact with the support, and a relatively movable 20 terminal to which the other end of the wire is attached.
3. A resistance element comprising a short-

circuiting conical conducting support, an uninsulated conducting wire coiled about said support in such manner that the individual 25 convolutions may be brought into contact with one another and with the support, and a relatively movable carrier to which the other end of the wire is attached.

4. A resistance element comprising a conical support, an uninsulated conducting wire coiled about said support in such manner 30 that the individual convolutions may be brought into contact with one another and with the support, and a relatively movable 35 terminal to which the other end of the wire is attached.

In testimony whereof I affix my signature, in presence of two witnesses.

JOSEPH A. MISLAND.
